UNITED STATES PATENT OFFICE.

GEORGE W. FERNALD, OF NEEDHAM, MASSACHUSETTS.

DOOR CHECK AND CLOSER.

SPECIFICATION forming part of Letters Patent No. 625,495, dated May 23, 1899.

Application filed March 16, 1898. Serial No. 674,003. (No model.)

To all whom it may concern:

Be it known that I, GEORGE W. FERNALD, a citizen of the United States, residing at Needham, in the county of Norfolk and Commonwealth of Massachusetts, have invented a new and useful Improvement in Door Holding, Releasing, and Checking Devices, of which the following is a full specification.

My invention relates to a device for regulating the action of door springs or weights; and it consists in so constructing and arranging the parts that the opening, holding open, and closing of the door are under perfect regulation and control.

Mechanism in which my invention is embodied is illustrated in the accompanying drawings, in which—

Figure 1 is a view showing in elevation a part of a door and its casing, showing one of my regulators in its simplest form. A door-spring is also shown. Fig. 2 shows, partly in plan and partly in section, the parts shown in Fig. 1. Fig. 3 shows in elevation parts of a door and frame having my invention attached, the door being closed. Fig. 4 shows the same parts as in Fig. 3, the door being open. Fig. 5 is a cross-section taken on lines 5 5 of Fig. 4. Fig. 6 is a view, partly in elevation and partly in section, of a modification to adapt my device to a door that swings in both directions. Fig. 7 is a plan view of the device as shown in Fig. 6. Fig. 8 is a cross-section taken on line 8 8 of Fig. 7.

In the drawings, Figs. 1 and 2, E represents a door, and E' its casing. The door is hung on ordinary hinges, as H, and a spring-hinge H'. Their parts are not new and need not be more fully described. To the casing E' a plate A is attached, to which plate A an air-cylinder C is made fast. This cylinder has a small outwardly-opening valve C'. A small opening is made in the cylinder and is partly closed by the loosely-fitting screw C². By adjusting the screw the amount of air admitted can be regulated at will. A closely-fitting piston B² works in the air-cylinder C. The piston B² has a rod B', the end of which is connected to the sliding block B. The block B has also attached to it by a pivot at D' a swinging arm D. This swinging arm D has at its outer end a series of holes D² D², (see Fig. 2,) adapted to receive the end of a vertically-disposed

pivot-pin D³, mounted on the bracket D⁴, attached to the door E. The several holes D² D² in the arm D are made for convenience in 55 adjusting the parts.

In the operation of the foregoing parts the opening of the door moves the pin D³ in the same direction, and this pin drawing on the arm D shifts the block B toward the cylinder 60 C and simultaneously pushes the piston-rod B' into the said cylinder and forces the piston B² gradually to the location of the valve C'. By this movement of the piston the said valve is 65 opened and the air in the cylinder escapes and the piston and relative parts assume the position shown by dotted lines in Fig. 2. When the door is closed either by the spring-hinge H' or by any other device, the piston B² returns against the pressure of the atmosphere or air, 70 there being created a substantial vacuum within said cylinder by said return of the piston, and as this forms an added but cushioned and yielding resistance to the force exerted by the said spring-hinge it follows that 75 the inward swing of the door is checked and softened when the piston is brought against the cushion resistance stated. When the piston passes the small opening controlled by the screw C², the air is drawn therethrough 80 into the cylinder behind or to the left of the piston for use during a successive opening operation. By the movement of the piston toward the left in the opening operation of the door a small portion of air in the cylinder 85 may pass out through the small opening controlled by screw C²; but the opening regulated by the valve C' being larger and offering comparatively no resistance the major portion of the air will outflow or escape therethrough. 90

The piston B² in the air-cylinder C is constructed as shown in Figs. 6 and 8, which may be described as follows: The rod B' has a screw-thread cut upon it, as shown, and has a fixed or check nut B³, against which the 95 yielding packing b² abuts. A second screw-nut B⁵ is located at the other end of the yielding packing b². This screw-nut B⁵ has points affixed to it, which are adapted to engage with holes made in the fixed disk B⁴. (See Fig. 8.) 100 Hence by turning the piston-rod B', thereby causing the screw-nut B⁵ to move against the soft packing b², the said packing may be compressed, so as to fit tightly in the cylinder.

For the purpose of automatically holding the door open I have the following-described device, (see Figs. 3, 4, and 5:—) A sliding casing F is mounted upon a fixed base-piece F'. 5 The motion of the sliding casing F is in a direction lateral to the movement of the block B. Its forward motion is given to it by the bent lever K K', pivoted at K². The bent lever K K' is arranged so that when the block 10 B comes in contact with it when the door is wide open it will act upon the pin F² in the casing F and throw the said casing forward. Within the casing a spring-bolt L is placed. This bolt L moves with the casing, but also 15 has a motion within the casing—that is, the spring F⁴, Fig. 5, throws it forward in advance of the casing when it is free and allows it to be forced back into the casing by the cam-piece L' under certain conditions, as will be 20 explained. The cam-piece L' has a notch L², with which the rounded end of the bolt L engages, as shown in Figs. 4 and 5. An electro-magnet M operates an armature M'. The said armature has a detent M², which is adapted to 25 engage with a corresponding detent F³ on the slide F and hold it forward, and thus cause the spring F⁴ to hold the bolt L forward in its engagement with the notch L² in the cam-piece L'. The armature M' is thrown forward 30 by the spring M³, so as to engage with and hold the casing F.

When the door is held open by the bolt L and it is desired to allow the door to close, the magnet M is energized by sending a current of electricity through it by a conveniently-located push-button.

The door is not held absolutely by the bolt L, as it has a rounded engaging end, and if the door is acted upon by any considerable 40 force the bolt will yield, it being held by the spring F⁴, and thus allow the block B to slide and the door to close.

In the modification shown in Figs. 6 and 7 the door is adapted to swing both ways and 45 the cylinder and its piston device is placed immediately over the door between it and the upper casing, as shown in the drawings.

I claim—

1. In a door check and closer, the combination with a cylinder, a piston therein, a sliding block operatively connected with the piston,

and mechanism for connecting the block to a door, of a locking-bolt arranged to engage the block, mechanism for tripping the bolt, and mechanism for retracting the bolt, substantially as specified. 55

2. In a door check and closer, an air-cylinder having a piston and sliding block attached, means for connecting the same to the casing and the door; a sliding bolt adapted to engage 60 with and hold the said sliding block, thereby holding the door open; an electromagnetically-controlled detent adapted to hold or release said sliding bolt, substantially as and for the purpose set forth. 65

3. In a door check and closer, the combination with a cylinder, piston, a sliding block operatively connected with the piston, and mechanism for connecting the block with a door, of a spring-actuated locking-bolt arranged to 70 engage the block, a trip-lever operatively connected with the bolt and in the path of the block, and mechanism for retracting the bolt, substantially as specified.

4. In a door check and closer the combination with a cylinder and piston, of a sliding block operatively connected with the piston and provided with a curved recess, a spring-actuated locking-bolt provided with a curved 80 end arranged to engage the recess, a detent for dogging the bolt in its locked position, mechanism for withdrawing the detent, and means for connecting the block with a door, substantially as specified. 75

5. In a door check and closer the combination with a cylinder, of a threaded piston-rod extending therein, a nut carried at the extremity of the rod, and a second nut upon the rod and expandable packing intermediate of the nuts, of a disk fixed within the cylinder 90 and coöperating mechanism carried by the last-named nut and disk to retain the nut against rotation whereby the packing may be expanded by the turning of the piston-rod, substantially as specified. 95

In witness whereof I have hereunto set my hand and seal.

GEORGE W. FERNALD. [L. S.]
